INVENTOR.

Horace N. Williams

UNITED STATES PATENT OFFICE.

HORACE N. WILLIAMS, OF PROVIDENCE, RHODE ISLAND.

GAS-PRODUCING APPARATUS FOR EXTINGUISHING FIRES AND OTHER PURPOSES.

No. 902,514.

Specification of Letters Patent.

Patented Oct. 27, 1908.

Application filed March 4, 1907, Serial No. 360,605. Renewed March 25, 1908. Serial No. 423,270.

To all whom it may concern:

Be it known that I, HORACE N. WILLIAMS, a citizen of the United States, residing at Providence, in the State of Rhode Island, have invented a new and useful Improvement in Gas-Producing Apparatus for Extinguishing Fires and other Purposes, of which the following is a specification.

The nature of my invention consists in the improved construction of an apparatus in which a jet of sulfuric acid is injected into a stream of water which passes through a chamber containing carbonate or bi-carbonate salts, for the manufacture of carbonic acid gas for various purposes, and especially for the purpose of extinguishing fires.

In the accompanying drawings, Figure 1 represents a side view of an apparatus embodying my invention. Fig. 2 represents a vertical axial section of the same.

In the drawings, Figs. 1 and 2, A represents the elongated copper receiving chamber provided with the closely fitting and firmly secured cover B, the said chamber being adapted to receive the several molded blocks C C C, of carbonate or bi-carbonate salts, which blocks constitute the working charge of the apparatus. At the forward end of the chamber A are placed the perforated baffle-plates D and E, which serve to prevent small fragments of the blocks C C from being carried forward into the contracted tapering passage F, and thus interfering with the proper flow of the solution through the said passage. To the rear of the chamber A is connected the pipe G, through which the water is caused to enter the said chamber. Above the elongated chamber A is placed the horizontally arranged elongated acid chamber H made of lead in order to resist the action of the contained sulfuric acid. The pipe J is connected with the inlet pipe G at the point a, and enters the said acid chamber H, at its rear and then extends downward to near the bottom of the said chamber, whereby the water flowing through the said pipe will enter the said chamber H at its rear, and at near the bottom of the contained acid.

The pipe K located at the forward end of the chamber H, extends downward to near the bottom of the acid in said chamber, and also extends from the chamber H to the center of the contracted passage F, and terminates in the contracted nozzle L. The chamber H is provided with the upwardly extend-

ing tube M, through which the acid is supplied to fill the said chamber, the said tube being closed by means of the tightly fitting screw-cap N. A line of hose O is attached to the inlet pipe G, and a line of hose P is also attached to the wall of the contracted delivering passage F.

In the operation of the apparatus, the receiving chamber A is to be properly charged with the molded blocks of carbonate or bi-carbonate salts C C C, hereinafter called carbonate, and the chamber H filled with the sulfuric acid I, then upon allowing the water under pressure to enter the inlet pipe G, the said water will pass into the chamber A, and after flowing around the said blocks of carbonate salts and dissolving a portion of the same will pass with rapidity and force through the contracted passage F into the hose pipe P, which leads to the fire. In the meantime a portion of the water from the pipe G, has passed from the said pipe through the pipe J, into the acid in the chamber H, and a corresponding quantity of acid has been drawn from the said chamber through the pipe K, and passed into the escaping carbonate solution, and upon the entrance of the sulfuric acid into the flowing solution a chemical combination will be effected whereby a great volume of carbonic acid gas will be produced, which gas will pass with the stream of water to the fire, and cause it to be extinguished.

I claim as my invention:

1. In an apparatus of the character described, the combination of the receiving chamber provided with a closely fitting cover, and the inlet pipe for directing the passage of the stream of water into the receiving chamber from a source of water supply under pressure, with the acid chamber having an inlet water pipe connected with the water supply pipe for the receiving chamber, and having an outlet pipe terminating within the cavity of the discharge outlet of the receiving chamber, for delivering the acid to the carbonate solution which flows from the receiving chamber whereby in the continual operation of the apparatus the contents of the acid chamber will be maintained under suitable water pressure.

2. In an apparatus of the character described, the combination of the receiving chamber provided with a contracted delivering end, and with a closely fitting cover at the opposite end, the inlet pipe for directing the passage of the stream of water into the

- receiving chamber, with an elongated acid chamber having at one end an inlet water pipe connected with the water-supply pipe for the receiving chamber, and with an outlet pipe located at the opposite end of the acid chamber, the said outlet pipe connecting with the discharge outlet of the receiving chamber and terminating at a point centrally of the said outlet, whereby the acid will be delivered centrally of the flowing stream of the carbonate solution.
3. In an apparatus of the character described the combination of the elongated horizontally arranged receiving chamber, provided with a contracted delivering end, and with a closely fitting cover at the opposite end, and the inlet pipe for directing the stream of water into the receiving chamber, with the elongated horizontally arranged acid chamber placed above the receiving chamber and having at one end an inlet water pipe connected with the water supply pipe for the receiving chamber and with an outlet pipe located at the opposite end of the acid chamber, the said

outlet pipe connecting with the discharge outlet of the receiving chamber.

4. In an apparatus of the character described, the combination of the receiving chamber provided with a closely fitting cover, and the inlet pipe for directing the passage of a stream of water into the receiving chamber from a source of water supply under pressure, with the acid chamber having an inlet water pipe connected with the water-supply pipe for the receiving chamber, and having an outlet pipe terminating within the cavity of the discharge outlet of the said receiving chamber and delivering the acid to the carbonate solution which flows from the receiving chamber, whereby in the operation of the apparatus, the contents of both the receiving and acid chambers will be held under suitable water pressure.

HORACE N. WILLIAMS.
